UNITED STATES PATENT OFFICE.

HARRY F. BLANCHARD, OF SOMERVILLE, MASSACHUSETTS.

HYDROCARBON-BURNER.

SPECIFICATION forming part of Letters Patent No. 779,065, dated January 3, 1905.

Application filed September 20, 1904. Serial No. 225,177.

To all whom it may concern:

Be it known that I, HARRY F. BLANCHARD, a citizen of the United States, residing at Somerville, in the county of Middlesex and State of Massachusetts, have invented new and useful Improvements in Hydrocarbon-Burners, of which the following is a specification.

This invention relates to certain new and useful improvements in that class of devices now generally known as "hydrocarbon-burners" and wherein a more or less heavy hydrocarbon is vaporized and the resultant gas is mixed with air and the combined vapors utilized for illuminating or heating purposes; and my invention consists of the parts and the constructions, arrangements, and combinations of parts, which I will hereinafter describe and claim.

In the accompanying drawings, forming a part of this specification, and in which similar characters of reference indicate like parts throughout the several views, Figure 1 is a vertical sectional view of a hydrocarbon-burner embodying my invention. Figs. 2 and 3 are side elevations. Fig. 4 is a plan view of the burner. Fig. 5 is an enlarged section on the line I I of Fig. 1. Fig. 6 is a section of the vaporizer-section detached. Fig. 7 is a cross-section on the line D D of Fig. 1.

In carrying out my invention I may use the same in connection with a tank or reservoir, (not shown,) from which leads a pipe 45, by which oil from the tank is supplied to the burner, said pipe being fitted to the lower base-section or starting heater portion 2 of the burner, which comprises a separate casting, with air and oil passages and controlling means which I will hereinafter describe.

Axially through the base or casting 2 is made an oil-passage *a*, which forms, substantially, a prolongation of the oil-supply tube, said casting having also in its lower portion a lateral passage *b* and circumferential air-inlets *e*, said lateral passage being controlled by a valve 5, having a threaded shank and an operating milled head or wheel, by which it may be adjusted in and out to regulate and control the oil, which may be allowed to flow through the passage to a channel *c*, leading to an an-

nular channel *d*, formed in the lower portion 50 of the base or casting 2.

The annular channel *d* is at the base of a trough or cup formed by two vertically-disposed concentric rings *R*, in which trough is placed a wick of asbestos or other absorbent, 55 incombustible, and indestructible material, which is designed to be saturated by the feed of oil through the oil-passage *a* and its branch *b* and the passages *c* and *d*.

The central portion of the base or casting 60 extends some distance above the trough and is of reduced diameter, so as to provide an annular air-space with which the air-inlets *e* communicate, and the upper end of the reduced central portion has a threaded nipple 65 adapted to be fitted to a companion member on the middle or vaporizer section, the construction and operation of which I will presently describe.

Surmounting the burner-trough is a chimney 70 formed of concentric rings 7 and 8, of foraminous material or of material provided with numerous holes for the admission of air, which is derived both from the outside and from the interior air-space which surrounds 75 the central portion or stem of the base or casting 2 and which air freely mingle with the vapors arising from the wick in the trough, and thereby promotes the combustion of the oil and insures the necessary heat for vaporizing the oil in the superposed vaporizing-chamber.

In order to facilitate the ignition of the wick, an opening is made in the outer chimney-ring 7 for the insertion of a lighted match 85 or taper, which opening is normally closed by the plate extension of a lever or finger-piece 9, pivoted at 10 and backed by an appropriate spring, as at 46, fixed to the base and having its free end pressing against the heel of the 90 lever or finger-piece. The pressure of the finger upon this lever will depress the spring and allow the lever to rock about its pivotal connection and uncover the match-opening, and when the pressure upon the lever is released the spring will close the plate extension of the lever against said opening, so that it will serve as a closure therefor.

As before stated, the vaporizer-section screws upon the upper threaded end of the central portion or shank of the base-section, and said vaporizer comprises a suitable casting with passages for the admission of oil and the circulation of the vapors generated therefrom. In the base of the vaporizing-section is formed an annular chamber *f*, to which leads a port or passage *g*, that is in open communication with the oil-passage *a* through the central part or stem of the base-section, whereby the oil from the supply-pipe 45 will under a suitable pressure that may be given to it flow through the passages *a* and *g* into the vaporizing-chamber *f*, where it is converted into vapor by the heat from the starting-burner formed by the wick and chimney, which are below and deliver the heat directly against the bottom of the vaporizing-chamber, as shown in Fig. 1, said vaporizer-section 11 having an apron or flange 11^a surrounding the upper part of the chimney 7 8 to better concentrate the heat from the latter against the bottom of the chamber *f*.

The vaporizing-section is somewhat enlarged at the base, and it forms a casing around the valve mechanism, gas-chamber, and vaporizing-chamber, to which latter the oil is led by the passage *g*, (which is inclined, as shown in Fig. 6,) a lateral channel *p*, and a vertical passage *o*, leading downward through the top of the chamber.

A threaded valve 28 is appropriately mounted in a seat in the vaporizer-casing, and this valve controls the flow of oil from the passage *g* to the lateral passage *p*, from which it flows to the aforesaid passage *o* into the vaporizing-chamber.

To facilitate the cleansing of the passages *o* and *p*, a screw or other plug 30 is removably fitted in the casing in line with the passage *o*, as shown in Fig. 3.

The valve 28 carries a worm 32, which rotates with the stem, but is splined thereto, so that the valve may move longitudinally relative to the worm, and the said stem passes through a threaded bushing or plug 31 to the outside of the vaporizer-casing, where it is provided with a milled head or wheel, by which it may be operated to control the passage of oil to the vaporizing-chamber.

Arranged in the vaporizer-casing at right angles to the needle-valve 32 is a gudgeon or pin 16, on which is turnably mounted a mutilated gear or segmental pinion 12, which is in mesh with the worm 32 on the stem of the valve 28, said gudgeon or pin having one end mounted in a bearing in the casing and the opposite end mounted in a plug 29, as shown in Fig. 7.

The segmental pinion is employed to operate a needle 15, and for this purpose it engages a rack-bar 13, having upper and lower stems 14, working in suitable vertical guides 14', formed in the vaporizer-casing, said up-

per stem having the needle 15 fixed to it and adapted to work through and maintain clean a small gas-outlet *k* in a plate 18, which is set flush with the top of a threaded nipple 17, screwed into the open top of the vaporizer-casing and which, with said plate 18, closes said top, said nipple carrying the upper guide 14' and having suitable passages *j* for the flow of gas from the gas-chamber *i* to the aforesaid hole or gas-outlet *k*.

Over the plate 18 and threaded plug 17 and screwing upon the upper end of the casing is a cap 34, having lateral air-ports *r*, to which cap the stem portion of the upper burner-casing 35 is fitted and which burner-casing in this instance is of shallow circular form and has an annular vaporizing-chamber *w* around its rim, which communicates with a gas-chamber *I* at one side.

A pipe 48 connects the vaporizing-chamber *f* with the vaporizing-chamber *w* of the burner and leads the gas from the former to the latter, while a second pipe 49 connects the gas-chamber *I* of the burner with the internal gas-chamber of the chamber *i*, the connection being by threaded pipes and unions, as shown at 51, and a diaphragm or partition 50', Fig. 5, forms two separated pockets *Y Y'*, to the former of which gas enters from the pipe 48, while from the latter the pipe 49 conducts the gas to the chamber *i*.

Within the burner-casing, which, as before stated, is of circular form and is recessed on top, are placed the rings or plates 36, 37, and 38, held together and to the casting by means of screws 44 or equivalent means. In or between the plates or rings 36 37 and the burner-casing are formed radial channels *Z*, which communicate with annular channels *a'*, with radial branches *v* leading to appropriate gas-burner outlets around the edges of the plates.

In the stem of the burner-casing is slidably mounted a tubular valve 39, whose lower open end receives the gas from the chamber *i* with the admixture of air from the ports *r*, said valve having its upper end adapted to enter openings in the center of the plates 36 and 37 to open or close the gas-passage of the valve, with the radial passages beneath any one or more of the burner-plates, according as more or less heat is desired for cooking purposes. The top of the valve has radial outlets which deliver the gas into the radial passages *Z*, and said valve has teeth upon its side forming a rack-bar with which engages a pinion 40, whose stem 41 passes outwardly through the casing and is provided with a milled head or wheel, by which the pinion is rotated to cause the valve to be raised or lowered relative to the plates 36, 37, and 38 to establish or shut off communication between the gas-supply and any one or more sets of radial channels *Z*. By this means gas may be supplied to the upper channels *v* only or the valve may be lowered to uncover the intermediate and lower radial

channels to supply gas to the channels *u* and *t* between the lower and intermediate plates, thus increasing the heating power of the burner. The annular vaporizing-chamber in the burner-casing is heated by the gas burning at the gas-outlets of the burner, and this insures the complete vaporization of any light oil which might be carried off by the gas generated in the primary vaporizing-chamber. 5

10 I do not claim in this application the lower or primary vaporizing means, the starting-burner, and the valve mechanism and gas-chamber, as these features form the subject-matter of a separate application filed by me of even date herewith and wherein the operation of said parts is set forth in detail and is substantially identical with the operation of corresponding parts of this application, the essential difference between the two applications 15 being in the construction and operation of the burner of this application and which burner is designed primarily for cooking and heating purposes.

Having thus described my invention, what 25 I claim as new, and desire to secure by Letters Patent, is—

1. In a hydrocarbon-burner a vaporizer-section with a primary vaporizing-chamber and internal gas-chamber, means for admitting oil 30 to said vaporizing-chamber, means for heating said vaporizing-chamber and means controlling the delivery of gas from the gas-chamber, in combination with a burner-casing having a vaporizing-chamber contained within its 35 rim, means connecting the primary and second-named vaporizing-chambers, means connecting the second-named vaporizing-chamber with the gas-chamber of the said vaporizer-section, a tubular, open-ended valve mounted 40 in the axis of the burner-casing, a series of concentric plates in the burner-casing with burner-outlets and intermediate gas-passages said 45 passages converging toward the center of the plates and adapted to connect with the upper end of said valve, and means for adjusting the valve relative to the plates to open and close communication with said passages.

2. In a hydrocarbon-burner having a vaporizer-section with a primary vaporizing-chamber and internal gas-chamber, valve-controlled means for admitting oil to said vaporizing-chamber, means controlling the delivery of gas from the chamber, means for supplying air to the gas delivered from the chamber, 50 a burner-casing of shallow annular form having a vaporizing-chamber inclosed by its rim, means connecting the vaporizing-chamber of the burner-casing with the vaporizing-chamber of the vaporizer-section, and means connecting the burner vaporizing-chamber with the gas-chamber of said section, means forming radial gas-passages in the burner-casing and gas-outlets leading through the top of the burner, a tubular open-ended valve mounted 55

in the axis of the burner and adapted to move 65 across the inlet ends of the gas-passages, to open and close communication therewith, and means for imparting a reciprocal movement to said valve.

3. A hydrocarbon-burner having in combination a burner-casing with a hollow rim forming a vaporizing-chamber said chamber divided at one side, means for admitting a gaseous fluid to said chamber, a second casing having an internal gas-chamber with a valve-controlled outlet, means for connecting said gas-chamber with the vaporizing-chamber of the burner-casing, a series of concentric plates in the burner-casing with radial and intermediate 70 annular gas-passages said radial passages diverging from the axis of the casing, a tubular open-ended valve reciprocable in the axis of the burner-casing and disposed at right angles to the plates, said valve having its lower end to connect with the gas-chamber of the said 75 second casing and having its upper end to connect with any one or more of the radial passages between said plates, said valve having, also, a rack on its outer surface, and a pinion engaging said rack to move the valve across 80 the entrances to the radial passages whereby gas may be supplied to any one or more of said passages.

4. A hydrocarbon-burner having a burner-casing with a tubular stem forming a part of 95 a gas-passage and means for admitting air thereto, said casing having a recessed top, a series of concentric, nested plates in the recessed top of the casing and means forming connecting radial and annular gas-passages 100 between adjacent plates said radial passages converging toward the center of the plates and leading to gas-outlets around the edges of the plates, a tubular valve, open at both ends and reciprocally mounted in said stem, and 105 having its upper end to move transversely across the inlets to the radial passages, to open and close any one or more thereof, and a rotatable pinion and rack-teeth on the valve engaged thereby for moving the valve relative to the passages.

5. In a hydrocarbon-burner, the combination with a primary vaporizer, oil and air supply mechanism associated therewith, and means for controlling the admission of oil and 115 the delivery of gas, of a burner-casing having an annular vaporizing-chamber contained within its rim, a series of concentric, nested plates within said casing said plates, except the uppermost one, having open centers and 120 annular gas-channels with passages radiating from the center of the plates and connecting with said annular channels, and means connecting the annular channels with burner-outlets at the edges of the plates, a tubular open-ended valve slidably mounted axially in the burner-casing, having one end connecting with the gas-supply and the opposite end to con- 125

nect with the radial passages between adjacent plates, means for adjusting the valve relative to said radial passages and means connecting the vaporizing-chamber of the burner-casing with the primary vaporizing-chamber and with the gas-chamber leading to the tubular valve.

In testimony whereof I have hereunto set my hand in presence of two subscribing witnesses.

HARRY F. BLANCHARD.
